UNITED STATES PATENT OFFICE.

MARSHALL B. LLOYD, OF MENOMINEE, MICHIGAN, ASSIGNOR, BY MESNE ASSIGNMENTS, TO HEYWOOD-WAKEFIELD COMPANY, OF BOSTON, MASSACHUSETTS, A CORPORATION OF MASSACHUSETTS.

REED-WEAVING MACHINE.

Application filed May 18, 1918. Serial No. 235,362.

To all whom it may concern:

Be it known that I, MARSHALL B. LLOYD, a citizen of the United States, and a resident of Menominee, county of Menominee, State of Michigan, have invented a certain new, useful, and Improved Reed-Weaving Machine, of which the following is a specification.

My invention relates generally to improvements in machines for weaving fabric of which reed fabric is characteristic, and which is composed of a plurality of spaced members called stakes, upon which long strands called fillers are woven, over some of the stakes and under others.

In manufacturing articles having a reed fabric it has been the universal practice prior to recent inventions of mine, among which may be noted especially my pending application, Serial Number 171,431, filed May 28th, 1917, to weave the fabric free hand with the stakes secured in the article frame and for the reed worker to shape the article in the process of weaving to the desired form, and while it may be possible that heretofore suggestions have been made toward the mechanical production of reed fabric, to the best of my extensive knowledge on the subject, no operable machine has been produced or was in operation prior to my above mentioned invention, but on the contrary, reed work throughout all of the great reed manufacturing plants was and is woven by hand in the same manner in which it has been woven for centuries.

It is an object of the present invention to provide means wherewith reed fabric can be successfully produced mechanically. Another object of the invention is to produce a reed weaving machine which shall be simple in construction; which shall require but little space; which shall produce in a given period many times the amount of fabric now producible by hand; which shall produce a fabric of greater uniformity and increased strength; which shall be operable by unskilled workers; which shall produce a given fabric with less material; which may be quickly made ready for the weaving operation, in which the woven fabric can be quickly and easily removed from the machine, and in which the various fabrics shall be substantially identical.

Other objects of my invention are to provide a weaving machine which can be constructed at a low expense and which can be maintained in working order with a minimum of attention and cost.

My invention consists generally in the form, construction, arrangement, and co-operation of the parts whereby the above named objects, together with others will appear hereinafter are attainable, and my invention will be more readily understood by reference to the accompanying drawings which illustrate that form of my invention which I consider the best at the present time.

In said drawings:

Fig. 1, is a general view in elevation of the machine showing a portion of the fabric completed (parts of machine being broken away to enable main members to be shown on larger scale).

Fig. 2, is a view, substantially on the line 2—2—2 of Fig. 1.

Fig. 3, is an enlarged plan view, substantially on the line 3—3 of Fig. 1.

Fig. 4, is a vertical section substantially on the line 4—4 of Fig. 3.

Fig. 5, is an enlarged detail sectional view substantially on line 5—5 of Fig. 4.

Fig. 6, is a detailed view in elevation of the mechanism contiguous the filler strand inserting point, illustrating the means for ejecting certain of the stakes outwardly and others inwardly, and for packing the filler strand.

Fig. 7, is an enlarged view, in side elevation, of the means for tensioning the filler strand.

Fig. 8, is an edge view of the mechanism shown in Fig. 7, portions thereof being broken away for illustrative purposes.

Fig. 9, is an enlarged view substantially on line 9—9 of Fig. 2.

Fig. 10, is an enlarged view substantially on line 10—10 of Fig. 1.

Fig. 11, is a general view in elevation of a modified form of my invention (parts being broken away for illustrative purposes).

Fig. 12, is an enlarged view substantially on the line 12—12 of Fig. 11 (feed screw not shown).

Fig. 13, is a view substantially on the line 13—13 of Fig. 12 (with parts of feed screw shown).

Fig. 14, is a plan view of one part or segment of the split nut used in that form of my invention shown in Fig. 11.

Fig. 15, is a detail view showing stake holding means of that form of my invention shown in Fig. 11.

Fig. 16, is a detail face view adjacent the filler strand inserting point of that form of my invention shown in Fig. 11; and Fig. 10 17 is a fragmentary face view illustrating a modified form of my invention in which means are provided for securing projecting stake ends of desired length.

That embodiment in my invention shown 15 in the drawings is characterized by or comprises generally the following parts: frame; stake holding and positioning means; stake manipulating and controlling means; filler strand inserting means; filler strand packing mechanism.

As a matter of convenience and in order to simplify and facilitate a description and understanding of the machine, I shall describe the parts generally in the order above 25 outlined.

The frame.

The frame in this instance comprises a base plate or portion 1, in which are secured 30 a plurality of spaced standards, 2, at the top of the standards and extending therebetween and supported thereby is a horizontal frame structure 3, composed of suitable cross or connecting members 3'. Carried by 35 the cross members 3' of the frame 3 and depending centrally thereof is a substantial bracket member 5, which is provided with spaced central bearing portions 6 and 7. In these bearing portions 6 and 7, I mount a 40 vertical shaft 8, for rotation, being properly supported against falling by means of the collars 9 and 10. Rotary motion is imparted to the vertical shaft 8 by means of the bevelled gear 11 secured to one end thereof, 45 which in turn meshes with the pinion 12 on the driven shaft 13. The shaft 13 is carried in suitable bearings 14 and 15 and may be driven at desired speed by any suitable means. In this manner it is obvious that 50 the vertical shaft 8 may be driven or rotated at any desired speed and against any forces tending to hinder its rotation. From this single vertical shaft, I secure all of the motions necessary, or rather impart motion to 55 all the mechanism necessary to manipulate the stakes; insert the filler strand; pack the filler strand into proper proximate relation with the pre-formed fabric; and successively and progressively move the finished woven 60 fabric away from the point of formation.

Stake holding and positioning means.

The stake holding and positioning means in this instance, is characterized by a circular band or ring 20, having a plurality of

spaced holes 21, of a size to accommodate the stakes 22 of the fabric freely therein, and in suitably spaced relation. The bottom of the ring 20 is imperforate and thus provides a rest or support for the lower ends of the 70 stakes. The function of this ring is to support the stakes and hold them in proper spaced relation until a sufficient number of convolutions of filler strand have been inserted to form a spacing belt. The width 75 or height of the circular band or ring 20 determines the length of stake projecting from the finished woven fabric. Longer lengths of stakes may be had by adjusting the stop 213 away from the ring 20 by the means indicated in Fig. 17. The filler strand is placed over and under the stakes and by the packing mechanism moved or packed into intimate relation to the top or upper portion of the band or ring 20; thus the band or 80 spacer 20 serves not only to space and hold the stakes in proper spaced relation, but also serves as a stop against which the filler strand is packed in the first stage of producing the fabric. Thereafter, as the successive 85 layers or convolutions of filler strands are inserted, the successive filler strands are packed against the pre-formed fabric, as will be better understood when a detailed description of the packing means is given. The 90 packing means in the normal operation of packing the filler strands serves to depress the fabric as it is completed, moving it away from the production point automatically.

In order that the stakes may be firmly 100 held in the ring 20, even though the holes 21 be relatively large, I prefer to provide an endless closely formed coil spring 23, the action of which will best be shown in Figs. 4, 5 and 6.

In Fig. 5 several of the stakes are shown 105 in place at the right hand part of the view being accommodated by moving the spring away from the inner wall 24 of the ring as indicated at 25. When no stakes are in position the spring hugs the inner wall of the ring as shown at the left hand portion of 110 Fig. 5. The spring is anchored against loss or dislodgment by means of a plurality of spaced vertical pins 26.

The ring 20, may be removed from the stakes after a number of layers of filler strands have been formed if desired, inasmuch as the stakes are then held by the formed fabric in proper spaced relation and in the instant case, in the form of a true circle, cylinder or tube, inasmuch as the mechanism here disclosed is formed to produce a tubular fabric of circular form. Or if desired the band or ring 20 may be left 120 in place on the stakes until the fabric is completed and then removed; replaced in starting position and new stakes 22 inserted in the spaced holes 21, ready for the production of another fabric.

The ring 20 is supported by means of a plurality of levers 27 pivotally mounted at 28 upon studs 29 secured in and depending from the plate or wheel 40. When the levers 27 are in the position indicated in Figs. 3 and 4, the edge portions 31, form a support for the ring. When the levers are swung the supporting ledge 31, is removed and the ring 20 may be removed or may move with the fabric. The ring 20 is properly spaced circumferentially by lugs 20' thereon which enter the space between adjacent studs or pins 41.

The completed fabric can be removed from the machine by simply severing the filler strands leading back to the reel and then pulling the fabric downwardly away from the point of formation and until it is free of the limiting means there positioned.

20 *Stake manipulating and controlling means.*

The stake manipulating and controlling means is characterized in this instance by a plate 40, which is of a circular form and of a diameter substantially equal to that of the diameter of the tubular fabric desired. Secured in the plate 40 and depending therefrom adjacent the periphery are a plurality of pins or studs 41, which serve a double function, to-wit: that of a gear acting to impart rotation to certain of the stake manipulating means and to the filler strand packing means, and second, as a stop against which the filler strand can be drawn or pulled in the formation of the woven fabric, thus serving as a template or fabric limiting device.

The plate 40 is mounted on the vertical shaft 8, and is keyed to the shaft so that it rotates therewith. In the edge of plate 40 I form a curved groove, 42, in which a portion of a helical spring 43 is accommodated. The spring 43 is of such size with relation to the plate 40 as to tend to compress itself on the plate and conform to the groove 42, and is formed with two complete convolutions for every stake of the fabric. The spring is so positioned with respect to the stakes that the stake can be moved into the contiguous V spaces formed by opposite portions of the spring, and is best shown in the Figs. 3 and 4. The stakes may move into the space a certain distance but cannot get out of the spring entirely, and the spring serves to carry the stakes in proper spaced relation during the interval in which the stakes are separated from the plate 40 for the insertion of the filler strands. The spring 43 is maintained against undesired shifting or circumferential creeping around the plate 40 by means of studs or pins 45 spaced circumferentially equi-distant between the stakes and a portion 45' of each pin is beveled so that in the event of the spring striking the pin as it returns to posi-

tion in the groove of the plate 40 after passing around the filler strand inserting means it will be shifted back into position. It is not thought necessary to describe in further detail the action of the spring at this point 70 and the function of the beveled studs or pins, inasmuch as that is shown and described in great detail in my co-pending application, Serial No. 171,431, heretofore mentioned. The plate 40 is provided with vertical grooves 47 for the accommodation of the stakes, these grooves permitting the stakes to lie slightly below or flush with the outermost portion 48 of the plate. Thus the upper or free ends of the stakes are held 80 in proper spaced relation and prevented from getting out of their proper grooves. In the present case a fabric is desired in which the filler strand passes over one stake and under the next adjacent stake and to 85 this end I provide means which moves every other stake out of its normal plane together with means for holding such projected or ejected stakes out for a period sufficient conveniently to insert the filler strand at which 90 time the stakes are permitted to return to their normal positions in the grooves of the plate 40, and in fact are actually positively returned to such positions. I also provide means whereby every other stake, to-wit: 95 the stakes which are not outwardly ejected are prevented from moving out of the grooves in which they normally lie or if they have for any reason moved out of the groove slightly, are positively returned to 100 such position so that they may freely pass the mechanism that inserts the filler strand in place.

The means here shown for ejecting the stakes outwardly comprises a wheel 50, having a plurality of projecting small teethlike portions 51. This wheel 50 is rotatably mounted by means of a stud 52 carried upon bracket 53 which is stationary relative to the plate 40 of the machine, being secured to the main depending bracket 5. The plate 40 carries spaced studs or pins 54, equal in number to the stakes of the fabric, and in this instance radially aligned therewith, and the wheel 50 carries a gear member 55 upon 115 its under side with which the pins 54 engage. Thus as the plate 40 is driven in the direction of the arrow, the wheel 50 is moved in the direction indicated by the arrow, and the teeth 51 thereof successively engage 120 alternate stakes moving them outwardly from the plate 40. The wheel 50 is arranged adjacent a somewhat diamond-shaped stake spreader 56, the teeth 51 of the wheel moving the stakes out a distance beyond the outer-side of the point 57 of the spreader. Once the stake reaches this position it is caused to move still further away from the plate 40 by engaging the body 125 portion of the spreader. In the center of the 130

spreader 56, I arrange a relatively narrow and small bladelike member 60, through the center of which the filler strand 62 passes, emanating from the lower end thereof, as is best shown in Figs. 3 and 6.

I prefer to provide in addition to the stake spreader 56, another lower stake spreader 56², which is similar in construction to the spreader 56, except that it is shorter and the end 56³ is somewhat closer to the member 60. There is a tendency at times for some of the stakes to spring out of their grooves, and I have so far found it desirable to prevent any likelihood of such action occurring either at the point where the filler strand is inserted or adjacent the points of the stake spreaders and to this end I provide positive means for insuring the retention of the stake in its proper groove and if necessary to return it to such position should it have moved therefrom prior to the time the point of the spreader is reached. The means herein shown for accomplishing this purpose comprises a wheel 70 having tooth-like projections 71, which engage alternate stakes, that is, the stakes that are not ejected outwardly by the wheel 50 carried by the bracket 53. This wheel 70 is carried upon stud shaft 72, mounted in a suitable bracket 73, secured to the frame of the machine, and is properly actuated by means of a gear member 74, secured upon the extended hub 74' and which engages the studs or pins 41, secured in and depending from the plate 40 of the machine, and which have heretofore been referred to as serving the combined function of a gear and of a template or fabric limiting means. The teeth 71 of the wheel 70, are cut away as indicated at 76 so as to avoid interference with the outwardly ejected stakes. In this manner the stakes are positively and accurately so disposed that they may pass freely upon the proper side of the stake spreaders 56 and 56² and permit the free insertion of the filler strand therebetween.

I might here state that in order to weave the fabric rapidly and yet keep the speed of the parts within reasonable limits, I find it desirable, though not necessary, to insert a plurality of filler strands at spaced intervals. In the instant case I have shown the filler strands inserted at two diametrically opposite points and with this construction a given fabric can be completed in half the time that would be required were a single filler strand employed, or the fabric may be produced in the same time with a machine operating at half the speed. When a single filler strand is employed, it is necessary that an odd number of stakes be used so that at each revolution the filler strand may pass over the stakes which it passed under on the previous revolution. Where two filler strands are inserted, as in the present case,

an even number of stakes are employed. Inasmuch as both filler strand inserting means are of the same construction, the detailed description heretofore given will serve for both.

70

Filler strand packing mechanism.

It is important that the filler strand be properly and uniformly packed if the resultant fabric is to be of a character suitable for use upon high class articles. This packing mechanism must not only pack the filler strand, but must also be so positioned and operate in such a manner as not to interfere with the insertion of the filler strand and to move the completed fabric progressively away from the weaving point. I have devised a very simple mechanism which accomplishes successfully these necessary and desirable functions. This means comprises a wheel 90 set at an angle to the vertical axis of the machine and mounted for rotation on a stud shaft 91 carried in a suitable bracket 92 secured to the frame of the machine. The wheel 90 is provided with a plurality of teeth 96 which mesh with the depending pins or studs 41 carried by the plate 40 which cause the rotation of the wheel, and as the wheel rotates, being at an angle, they move from an elevated point when first engaging the pins 41 to a relatively lower position when leaving the pins. Thus as the filler strand is brought from the point of insertion under the wheel, as shown, the successive incoming portions of the filler strand are progressively moved from their inclined position relative to the pre-formed fabric to a position parallel to and closely contiguous the previously inserted filler strands. Of course, in the starting of the machine the filler strand is packed by means of the wheel 90 into parallel relation and intimate association with the top of the spacing ring or holder 20.

The packer wheel, 90, is adjustable, as is clearly shown in the drawings, in every direction, to-wit: rotatably, in vertical and horizontal planes and vertically. The vertical adjustment and the rotary adjustment in a horizontal plane is had by virtue of the bracket 92' which has a cylindrical stud portion clamped in the bracket 92''. The bracket 92'' in turn carries a cylindrical stud upon which the bracket 92 is mounted which stud is clamped in place, and which may be rotated to swing the bracket 92' in a vertical plane. This enables placement in any position that may be found most desirable for the particular work in hand.

Reed tensioning and dispensing mechanism.

As before stated, it is very important that the tension of the filler strand be maintained constantly to just the right extent if the fabric is to be uniform in appearance and

125

130

strength. Especially is this so where two or more strands are woven simultaneously. I have devised a novel mechanism whereby the filler strand tension can be maintained uniformly throughout the entire extent of the fabric and irrespective of the amount of reed which may be upon the reel. Where a multiple feed is employed, such as shown in the instant case, not only is it desirable that the tension be uniformly maintained upon each filler strand but it is also desirable that the amount of material inserted at the two feed points during a given period of rotation, be practically the same or there will be a noticeable looseness in one of the filler strands as compared with the adjacent filler strand. The filler strands are carried upon suitable reels 100 and 101 from which they pass through tensioning means, 102 and 20 around tensioning mechanism 103, thereafter passing to the filler strand inserting means over suitable guide rollers, 104 and 105. The tension means 102 as is best shown in Figs. 1, 7, and 8, comprises two channel members 102^a and 103^a through which the filler strands from respective reels pass. The filler strands are frictionally restrained in their passage through the channels by means of levers 104^a and 105^a and the actuating springs 106^a and 107^a. The filler strands then pass through eyes 108 and 109 to the tension means 103. The means 103 consists of a wheel having two beveled or angled faces 140 and 141 which are bounded by flanges 142, 143 and 144. The wheel is mounted upon a stud shaft 145 suitably carried in a bracket 146. The filler strands pass to the upper part of the wheel faces 140 and 141, thence completely around the wheel and finally leave the wheel from the lower portion of the inclined face. Each particle of reed must pass substantially twice around the tension wheel and is therefore always properly tensioned. The faces 140 and 141 being of identical size and moving together, necessarily pay out accurately measured quantities of filler strand to each feed point. In order to adjust the tension upon the reed, I provide a threaded bolt, 165, extending from stud 145 and thereon I mount a lever 166 having opposite arms or wing portions 166^a and 166^b. Interposed between discs 166^c and 166^d and abutting the outer faces of the tension wheel, I place fibre discs 168 and 168'. The pressure of these against the wheel can be changed by rotating lever 166, which in turn acts upon the flat spring 166^e. The lever 166 can be rotated conveniently by the operator through the medium of cords or cables 166' and 166''. By the means described the tension of the filler strand can be minutely altered to provide just that degree of tension which gives the best results for the particular filler strand employed and for the fabric desired.

General operation of the machine.

Having thus described in detail the various structural features and their co-operative relation, I shall briefly state the operation of producing a completely woven fabric thereon. To this end let us assume that the band 20 has been removed from the machine. The band 20 is first placed in position, encompassing the pins and being circumferentially positioned by lugs, 20'. With the parts in this position, the various stakes are placed through the holes in the band 20, the ends of the stakes resting upon the flicor or stop 213 of the ring. The filler strands may be then threaded over and under the stakes from the point of entrance to the belt or band 20 along the general curved line defined in the drawings or I find that the machine can be started without threading the filler strand over or under these stakes by simply pulling from the reel a sufficient length of filler strand because when the machine is started the filler strand is automatically laid into position and carried from the entrant position down to the band or belt. Continued rotation of the machine upon the vertical shaft 8, quickly lays in sufficient filler strands to form a belt of fabric. The fabric being formed around the pins 41, and being placed tensionally thereon is held on the pins with sufficient force or friction to support itself and prevent its falling and in fact to require the positively downward movement of the packing means to depress it as it is successively formed. In this manner the formed fabric is progressively moved downwardly and when the proper height of fabric is produced the machine is stopped, the incoming filler strands severed and the fabric removed. As before stated, the ring or band 20 may be removed either after several of the layers or convolutions of filler strands have been formed or it may ride with the fabric until the complete fabric is produced and then removed. At any rate it is ultimately removed from the completed fabric and repositioned as above described.

There are other ways in which the machine can be made ready for the weaving operation all of which will readily suggest themselves from this detailed disclosure.

One further point should be noted and that is that a guard 130 is provided just preceding the filler strand inserting point 120 whereby any stakes which may project outwardly to an undesired extent will be moved inwardly at that point. (See Figs. 6 and 9.) Substantially at the weaving points I prefer also to provide guard or limit members 131 (see Fig. 10).

Inasmuch as this complete disclosure will readily suggest to others modified structures whereby the substantial objects of my invention may be attained, I do not wish to 130

be limited to the specific construction herein shown and described, except only as may be necessary by limitations in the hereunto appended claims. For example, while in the 5 mechanism thus far described, the fabric is formed in a given plane and then moved downwardly, it may be woven in this or some other place and moved upwardly. A 10 structure will now be described for accomplishing this result.

Modified weaving mechanism.

In Fig. 11 of the drawings I have shown 15 a machine in which the fabric is moved upwardly after it is formed instead of downwardly as in the case first described. Also, it will be understood that in this instance the stakes will initially project downwardly from the weaving point whereas in the first 20 case they initially extended upwardly from the weaving point. The parts whose function is the same as in the first form have been given similar reference characters even though the positions thereof may be different. An easy way to consider the matter 25 is to think of the machine as merely turned upside down.

When the fabric is to be moved upwardly as formed, I prefer to provide other means 30 in addition to the packing means for this purpose. The means here shown comprises a stationary central upstanding threaded rod or screw 200, over which a sleeve 201 slides. The lower end of the sleeve carries 35 a "split" nut comprising three segments 202 which are pivoted at 203, and which have screw faces 204. When the machine is weaving the screw faces of the segments coact with the screw 200. The sleeve (201) is 40 connected to the stake ring by truss rods 205 and 206, so that the stake ring is supported from the sleeve. The plate 40 in this instance is provided with a plurality of long upstanding rods 207, which pass 45 through holes in the stake ring and which drive the stake ring in unison with the plate 40. Therefore, as the stake ring rotates like rotation is imparted to the sleeve 201 which in turn climbs the screw thus carrying the stake ring and fabric. In order 50 that stake ring can be quickly returned to starting position after fabric is completed, I provide a cam, 208, having a plurality of cam grooves, 209, in which studs 210 of the 55 split nut segments operate. It is obvious that rotation of the cam in the direction of arrow (see Fig. 12) will move nut segments outwardly and disengage them from screw 200, thus permitting quick return to starting 60 position. The pitch of screw threads on rod 200, it will be understood are such as to elevate the stake ring a distance substantially equal to the thickness of the filler strand during each revolution.

65 That form of my invention just described,

preferably has screw or other means of moving the fabric as it is formed whereas in the first form I do not require such mechanism. It is of merit especially for producing a long fabric for the reason that the stakes 70 hang from the weaving point and by gravity tend to remain in their normal weaving planes.

In Fig. 15 the stakes are shown as comprising cores 211 of wire over which fibre or 75 paper 212 is wrapped or wound. This is depicted to illustrate that the machine may be used either with the natural reed, so-called fibre reed, or a composition of metallic core and fibre skin. When fibre reed is 80 used I prefer the metallic center for the stakes.

The stake stop or ring 213 is detachably secured to the band 20, as shown in Fig. 15, as by means of machine screws 213', or the 85 ring 213 may be adjustably secured to the band 20, whereby projecting stake ends of desired length may be provided. Such a construction is shown in Fig. 17, the ring 213 being secured by a plurality of lugs 90 213^a (only one shown in the fragmentary view), which lugs are vertically slidable upon standards 213^b (only one shown). The lug 213^a obviously may be fixed against movement on the standard 213^b by means of 95 set screw 213^c. Secured to the ring 213 are a plurality of swivel lugs 214, between which and the ring the ends of the stakes are held fast preventing the fabric becoming detached from the band 20 during the 100 process of weaving.

That form of my invention shown in Fig. 11, and the following figures, preferably is provided with the curved guard member 60' for the purpose of preventing any danger 105 or possibility of long stakes becoming entangled at the point where they are acted upon by the mechanism that ejects alternate stakes to permit insertion of the filler strand.

110 I claim:—

1. An apparatus for weaving reed fabric and the like having stakes and a filler strand embodying therein fabric limiting means, means for holding the stakes in weaving relation thereto, means for forming a progressive shed of the stakes and for laying the filler strand in and out of the shed, and means for packing the filler strand and for moving the fabric away from the fabric 115 limiting means after it is formed.

2. An apparatus for weaving reed fabric and the like having stakes and a filler strand embodying therein fabric limiting means, means for holding the stakes in weaving relation thereto, filler strand tensioning means, 120 means for forming a progressive shed of the stakes and for laying the filler strand in and out of the shed, the tension being such as to hold the fabric on the limiting means with 125 130

sufficient friction to require positive means to move it way from the fabric limiting means after it is formed and means for moving the formed fabric away from the fabric limiting means.

3. An apparatus for weaving reed fabric and the like having stakes and a filler strand embodying therein gear-like fabric limiting means, means for holding the stakes in weaving relation thereto, and means actuated by the gear-like limiting means for packing the filler strand and for progressively moving the fabric away from the fabric limiting means after it is formed.

15 4. An apparatus for weaving reed fabric and the like having stakes and a filler strand embodying therein fabric limiting means, movable stake holding means positioning the stakes in weaving relation to the fabric limiting means, means for forming a progressive shed of the stakes and for laying the filler strand in and out of the shed, said means including means for moving the filler strand from its initially inserted position toward the 20 stake holding means and for moving the finished fabric and stake holding means away from the fabric limiting means.

5. An apparatus for weaving reed fabric and the like having stakes and a filler strand embodying therein fabric limiting means, means for holding the stakes in weaving relation thereto, means for forming a progressive shed of the stakes and for laying the filler strand in and out of the shed, said 30 means including common means for packing the filler strand and for moving the fabric away from the fabric limiting means after it is formed, and pay-out mechanism for issuing desired measured lengths of filler strand.

40 6. An apparatus for weaving reed fabric and the like having stakes and a filler strand embodying therein gear-like fabric limiting means, means for holding the stakes in weaving relation thereto, means for forming a progressive shed of the stakes and for tensionally placing the filler strand in and out of the shed, thereby frictionally holding the fabric on the limiting means against undesired movement, means actuated by the 45 gear-like limiting means for packing the filler strand, and pay-out mechanism for issuing desired measured lengths of filler strand.

55 7. An apparatus for weaving reed fabric and the like having stakes and a filler strand embodying therein fabric limiting means, having rounded outer surfaces, means for holding the stakes in weaving relation thereto, means for forming a progressive shed of the stakes and for laying the filler strand in and out of the shed and for moving the fabric away from the fabric limiting means after it is formed.

60 8. An apparatus for weaving reed fabric

and the like having stakes and a filler strand embodying therein fabric limiting means, having rounded outer surfaces, means for holding the stakes in weaving relation thereto, and means for forming a progressive shed 70 of the stakes and for laying the filler strand in and out of said shed, said means including common means for packing the filler strand and for moving the finished fabric away from the fabric limiting means after it is 75 formed.

9. An apparatus for weaving reed fabric and the like having stakes and a filler strand embodying therein fabric limiting means, means for holding the stakes in weaving relation thereto, means for forming a progressive shed of the stakes and for laying the filler strand in and out of the shed, said 80 means including common means for packing the filler strand and for moving the fabric away from the fabric limiting means after it is formed and said filler strand laying means also including mechanism for restoring to their normal planes, prior to the filler strand inserting point, any stakes that 85 may have moved therefrom.

10. An apparatus for weaving reed fabric and the like having stakes and a filler strand embodying therein fabric limiting means, means for holding the stakes in weaving relation thereto, means for forming a progressive shed of the stakes and for laying the filler strand in and out of the shed, means for moving the fabric away from the fabric limiting means, after it is formed, said filler 90 strand laying means including mechanism for restoring to their normal planes, prior to the filler strand insertion point, stakes which may have moved therefrom accidentally, mechanism for moving desired stakes away 95 from their normal planes, and mechanism engaging the fabric limiting means and being operated thereby.

11. An apparatus for weaving reed fabric and the like having stakes and a filler strand embodying therein fabric limiting means, means for holding the stakes in weaving relation thereto, means for forming a progressive shed of the stakes and for laying the filler strand in and out of the shed, said 110 means including means for moving the fabric away from the fabric limiting means as it is formed, and comprising a toothed wheel angularly disposed with respect to the stakes.

12. The herein described stake-holding means comprising a ring formed with a groove in one of its vertical faces, a plurality of spaced stake-receiving holes, and a coil spring in said groove normally adjacent the bottom of the groove and acting to grip the stake ends when they are inserted between the spring and the bottom of the groove.

13. The herein described stake holding means comprising a ring formed with a 130

groove in one of its vertical faces, a plurality of spaced stake-receiving holes and a coil spring in said groove normally adjacent the bottom of the groove and acting to grip the 5 stake ends when they are inserted between the spring and the bottom of the groove together with spaced pins secured in the stake

holding ring and passing through loops in the coil spring to hold same in desired position.

10

In testimony whereof, I have hereunto set my hand this 23rd day of April, 1918.

MARSHALL B. LLOYD.
